ELECTRIC HEATER CASING

Jon W. Hauser, St. Charles Township, Kane County, Ill.,
assignor to McGraw-Edison Company, Elgin, Ill., a
corporation of Delaware

Application March 5, 1958, Serial No. 49,913

Term of patent 14 years

(Cl. D81—10)

Figure 1 is a perspective view of an electric heater casing embodying my design;

Fig. 2 is an elevational front view thereof, the back being plain; and

Fig. 3 is an elevational side view.

The dominant features of my design reside in the portions shown in solid lines.

I claim:

The ornamental design for an electric heater casing, substantially as shown and described.
